Attorney

UNITED STATES PATENT OFFICE.

HENRY F. KELLNER, OF SILVER LAKE, KANSAS.

JETTY CONSTRUCTION.

1,281,022.

Specification of Letters Patent.

Patented Oct. 8, 1918.

Application filed April 27, 1918. Serial No. 231,191.

To all whom it may concern:

Be it known that I, HENRY F. KELLNER, a citizen of the United States, residing at Silver Lake, in the county of Shawnee and State of Kansas, have invented certain new and useful Improvements in Jetty Construction, of which the following is a specification.

This invention relates to an improvement 10 in jetty construction, and has for one of its objects to provide self sinking, angular frames or deflectors of such construction that they will engage the bed of a water channel to advantage and will not be readily 15 overturned by a water current. The invention also relates to deflectors so constructed that strands, when connected to opposed parts thereof will operate to advantage in maintaining the deflectors substantially in 20 line. The invention also has reference to simplicity and durability of parts so that its manufacture will be practical, convenient and economical.

The novel features of the invention are 25 fully described herein and are pointed out in the appended claims, and are illustrated in the accompanying drawing, wherein,—

Figure 1 is a perspective view of one of the angle irons employed. Fig. 2 is a perspective view illustrating a plurality of angular frames or current deflectors maintained in line in a silt bearing stream. Fig. 3 is a side or end view of a current deflector, the strands being omitted. Fig. 4 is a side 35 or end view of a current deflector provided with cables or strands.

I provide a plurality of angular frames or current deflectors 5, each consisting of strips or bars of angle irons, substantially of 40 uniform length, as the strips 6, 7 and 8, each strip or bar, as best shown in Fig. 1, having one of its flanges provided with apertures 9, its other flange being provided with apertures 10, said apertures 9 and 10 being disposed midway between the ends of the strip, each strip also being provided near its respective ends with apertures 11 formed in each flange.

By use of the strips thus described an 50 angular frame may be conveniently assembled which, when placed in swiftly moving water will not be readily dislodged or overturned, since it will provide three prongs, as will be seen, which will engage 55 the bed of the channel, each flange of an angle iron being in engagement with a flange

of an adjacent angle-iron strip, rivets or equivalent keepers 12 being employed and traversing the apertures 9 and 10, and thereby providing a connection for the strips midway between their ends, each end of each strip being connected with an end of each of the remaining strips by means of strands 13, whereby stresses directed to the outwardly projecting prongs or end portions of 65 the strips will be adequately resisted.

Means are provided for maintaining the angular frames thus provided in connected relation when placed in a stream or water channel, as the strand 14, which is secured 70 to each frame at its middle, and which is secured to an anchor-post 15 upon the bank, as shown in Fig. 2.

Also means are provided for preventing inversion of the deflectors or frames, consisting of the strands 16 and 17, these being secured, respectively, to the two adjacent upper ends of two of the strips of each deflector, the strand 16 being secured to an anchor-post 18 on said bank and the strand 80 17 being secured to the anchor-post 19 on the bank. It will be understood that if the posts 18 and 19 are spaced apart transversely of the line of the deflectors, as shown in the drawing, this arrangement will tend 85 to prevent inversion of the frames, and on account of their form and weight, the frames will so engage the bottom of a channel that they will be maintained in line transversely thereof except in instances 90 where the water moves very swift, and in such instances additional anchorage (not shown) may be provided.

The construction thus described is of great 95 advantage in the formation of alluvial deposits in silt bearing streams. Since all of the parts are constructed of iron, the frames will readily sink, and on account of the peculiar form for the frames they will resist the force of moving water, the outwardly 100 divergent prongs normally engaging the bed of a stream regardless of the position of the frames.

In operation, several of the frames may be connected and secured to the bank 20 of 105 a stream 21, the straight or curved line of the connected frames 5 being transverse to the flowing water and disposed at any desired angle with reference thereto; and water carrying silt or sand and moving in 110 the direction indicated by the arrow shown in Fig. 2, will cause alluvial deposits 22

below or "down stream" from the deflectors or frames 5, the object, in some instances, being to prevent the water from cutting away the land or banks of a stream; 5 also to change the direction of water currents, and also to cause accumulation of land at a water front. In the formation of jetties in tide waters the frames, when connected, are disposed transverse to the flow 10 of the tides, the result being that sand bars will form at each side of the line of the connected frames, and since the frames are durable and on account of their form, they tend to maintain the sand-bars as permanent 15 supports for a roadway or for piers or wharves.

Having fully described my invention, what I claim and desire to secure by Letters Patent is,—

- 20 1. In jetty construction, a plurality of current deflectors disposed substantially in line in a water current, each consisting of a pair of bars of angle iron disposed at right angles and connected midway between their ends and a third bar of angle iron disposed at right angles to each bar of the first pair of bars of angle iron and connected therewith midway between its ends.
- 25 2. In jetty construction, a plurality of current deflectors disposed substantially in line in a water current, each consisting of a trinity of apertured angle-iron strips sub-

stantially of uniform length and disposed substantially at right angles with reference to each other, each flange of a strip being 35 disposed in engagement with a flange of the other two strips, rivets traversing the apertures of the engaging flanges, and metallic strands connecting the terminals of each strip with the terminals of the remaining 40 strips.

3. In jetty construction, a plurality of current deflectors each consisting of a pair of strips of angle iron disposed substantially at right angles and engaging each other midway between their ends, a third strip of angle iron disposed at substantially right angles to each strip of the first pair and connected therewith midway between its ends, strands connecting the ends of each 50 strip with the ends of the other strips of angle iron, a cable connected with a strip of each deflector, a second cable connected with a strip of each deflector, said cables being secured to a stationary support for maintaining the deflectors in line while disposed in a water current.

In testimony whereof, I have affixed my signature in presence of two witnesses.

HENRY F. KELLNER.
